(57) **CLAIM**

The ornamental design for a patch, as shown and described.

DESCRIPTION

FIG. 1 is a perspective view of a patch showing my new design;

FIG. 2 is a front elevational view thereof, the rear elevational view being a mirror image of the front view shown;

FIG. 3 is a top plan view thereof;

FIG. 4 is a bottom view thereof;

FIG. 5 is a right side view thereof, the left side view thereof being a mirror image of the side view shown; and,

FIG. 6 is an enlarged cross-sectional view taken along line 6—6 of FIG. 2.
